UNITED STATES PATENT OFFICE.

RUDOLPH OBERWIMMER, OF NEWARK, NEW JERSEY.

GAME APPARATUS.

SPECIFICATION forming part of Letters Patent No. 509,179, dated November 21, 1893.

Application filed April 22, 1893. Serial No. 471,428. (No model.)

To all whom it may concern:

Be it known that I, RUDOLPH OBERWIMMER, a citizen of the United States, residing at Newark, in the county of Essex and State of New Jersey, have invented certain new and useful Improvements in Game Apparatus; and I do hereby declare the following to be a full, clear, and exact description of the invention, such as will enable others skilled in the art to which it appertains to make and use the same, reference being had to the accompanying drawings, and to letters and numerals of reference marked thereon, which form a part of this specification.

15 The object of this invention is to provide an interesting game for those who wish to amuse themselves, in this manner, during their leisure hours; and the game is designed to be played by two persons only.

20 The invention consists in the improved game-apparatus and in the arrangement and combination of the several parts thereof, as herein set forth and finally pointed out in the claim.

25 Referring to the accompanying drawings, in which similar letters and numerals of reference designate corresponding parts in each of the several figures where they occur, Figure 1, represents, in plan, a game-apparatus 30 embodying my improvements, and Figs. 2, 3 and 4, are detail views, also in plan.

In said drawings, A, A, designate, or are intended to represent the American or United States flag, which is painted or impressed 35 upon a board, A', of wood, paper, or other desired material, substantially in the manner shown, and B, B, represent the flag-staffs, crossing each other.

40 C, D, E, represent three circular or other shaped marks or characters, designated herein as fields, one of which is located between the flag-staffs and one on each side thereof, below the flags, each being of a different color from the others, preferably the national colors, 45 red, white and blue, C, being the red, D the white and E the blue. Immediately below each flag is outlined a series of circular or other shaped figures, 1, 2, 3, 4, 5, and upon each flag are twenty stars or other marks, in 50 the field or space usually provided therefor.

Upon each of the four red or white stripes which project from the star-field is a series of five dots or marks, a, twenty in all, which, in playing, are designed to be covered by disks or buttons, b, one player using red and 55 the other white, or other contrasting colored buttons or disks, which they move alternately, as hereinafter set forth; each player being provided with twenty buttons one set being white and the other red, and twenty 60 stars, c, or other-shaped pieces. Dice, d, three in number, are also used, in playing the game, but they are marked differently from ordinary dice, in that their faces are of contrasting colors, preferably red, white and blue, 65 two opposite sides being red, two opposite sides white and two opposite sides blue.

The game is played as follows, to wit:— First each player places his buttons, b, which are all of one color, one set being white and 70 the other red, upon the shorter stripes of his chosen flag, as indicated by the dots, a, in Fig. 1. One of the players then throws the dice and, in accordance with the colors which are shown on the top thereof, moves one of 75 the buttons. For example, if he holds the white buttons and throws two reds and one white, he is entitled to move one of his buttons from the lowest of the short stripes to the next correspondingly colored stripe below; if he throws one red, or one blue, and 80 two whites, two moves, or to the second stripe below; if he throws three whites, three moves, or to the third stripe below, or he can move three separate buttons to one stripe below, 85 and so, in the case of two moves he can move two separate buttons to one stripe below if he chooses to do so; if he throws two reds and one blue (none of his own color) he loses his move and gives his opponent, who holds the 90 red buttons, one move; if he throws three reds he loses his move and gives his opponent two moves.

The player, holding the red buttons, who alternates with his opponent in throwing the 95 dice and moving, is entitled to move as follows, to wit: if he throws one red and two whites, to one move; two reds and one white or two reds and one blue, to two moves; if three reds, to three moves; if he throws two 100

- whites and one blue, he loses his move and gives his opponent the right to one move, and if he throws three whites he loses his move and gives his opponent two moves. When 5 either of the players reaches the last of the longer stripes with any of his buttons his next move entitles him to place his button upon one of the spots or figures 1, 2, 3, 4 or 5, immediately below his flag.
- 10 If either player throws a red, white and blue, he is entitled to move one button from one of the spots 1, 2, 3, 4, 5, immediately below his flag to the field D or E of his own color. If he has no button on the spots 1, 2, 15 3, 4, 5, he is entitled to one move toward such spots. If he meets his opponent on the red or white field they immediately raffle for the better position, to wit—the blue field, E, and the player who throws the most blues is en- 20 titled to move his button to the blue field; the game then proceeds as before. The same throw, (red, white and blue,) also entitles the thrower to move a button from the red or white field, if he has one thereon, to the blue 25 field, or, if he has a button on the latter, to exchange it for a star, c, (each player being provided with twenty) which he places over one of the stars on his flag and removes the button for the balance of the game.
- 30 If either player throws three blues he is entitled to remove one of his buttons, preferably from the upper row, and place a star in the star field. If either throws two blues and one red, he is entitled to move one button 35 from the spots 1, 2, 3, 4, 5, if he has one thereon, to the red field; or if he throws two blues and one white, to the white field; should he in either case meet his opponent with a but-

ton thereon, they then proceed to raffle for the better place, to wit the blue field, the one 40 throwing the most blues placing his button thereon, as explained above.

The player who first fills his star-field with twenty stars wins the game.

The players must not forget that to move 45 a button to the red or white field it must have reached one of the spots, 1, 2, 3, 4, 5, as otherwise he is only entitled to one move, on the flag, or from it to the said spots.

Any other arbitrary marks may be substi- 50 tuted for those on or below the flags.

Having thus described my invention, what I claim, and wish to secure by Letters Patent, is—

The game apparatus herein described, which 55 consists of a suitable board or tablet having imprinted thereon two flags; a series of stars in a field at the upper corners, adjoining the staff; a series of dots or marks on four of the stripes projecting from the star-field, equal 60 in number to the stars; a series of five marks or spots immediately below each flag; and three fields of contrasting colors, as red, white and blue, respectively; forty disks or buttons, forty stars or other shaped pieces and three 65 dice; separate from and independent of the game-board; the whole being arranged and adapted to operate as herein set forth.

In testimony that I claim the foregoing I have hereunto set my hand this 18th day of 70 April, 1893.

RUDOLPH OBERWIMMER.
